UNITED STATES PATENT OFFICE

ALBERT B. MILLER AND WALTER H. KELLNER, OF GREEN BAY, WISCONSIN

GAS HEATER

Application filed May 11, 1929. Serial No. 362,220.

This invention appertains to heating appliances and is an improvement on our prior Patent 1,623,487, granted to us April 5, 1927.

One of the primary objects of our invention is to provide a novel gas heater primarily intended for the use of heating houses and the like, and which is adapted to be suspended beneath the floor of a room or hall of the house to be heated and which embodies novel means for carrying off all fumes generated by the burner exteriorly of the house and thereby eliminate all danger incident to the use of gas heating appliances.

Another important object of our invention is the provision of novel means for leading fresh air to the burner from the exterior of the house and novel means for carrying the fumes from the burner out of the house, with novel means for permitting the air to be heated for circulating about the burner and its associate parts up into the house or room to be heated, the air being heated being entirely independent of the air utilized for supporting combustion in the burner.

A further object of our invention is the provision of a novel conical air heating baffle arranged on the burner, the conical baffle including a plurality of hollow radial fins through which the flame and products of combustion flow, the air to be heated for the house circulating around the radial fins and thence into the house.

A further object of our invention is the provision of an annular fume drum receiving the products of combustion from the conical baffle, the drum having a pipe communicating therewith for leading the products of combustion exteriorly of the house, the drum also forming means for heating the air circulating about the same.

A further object of our invention is the provision of a humidifying cup carried by and sealing the lower end of the conical baffle with means for maintaining a constant supply of liquid in the cup, whereby the heated air will be humidified prior to the delivery thereof into the house, the cup having a ground connection with the conical baffle to prevent the entrance of fumes from the burner into the air being heated.

A further object of our invention is the provision of novel means for controlling the air to the burner, a certain portion of the air being delivered above the burner and a certain portion to a gas mixing chamber communicating with the burner, and a valve plate for controlling the flow of air into the mixing chamber.

A further object of our invention is the provision of a circular baffle plate surrounding the conical baffle and fume drum, which serves as means for leading the air to be heated toward the burner, baffle and heating drum and also as means for keeping the casing in which the burner is disposed in a cool condition.

A further object of our invention is the provision of novel means for leading the fume pipe through the fresh air pipe for the burner, whereby the fresh air pipe will serve as a protector for the fume pipe and as means for permitting the preheating of the fresh air prior to the delivery thereof to the burner.

A still further object of our invention is to generally improve the construction of our prior patent, above mentioned, and to provide a gas burner which will be durable and efficient in use, one that will be simple and easy to manufacture and one which can be placed upon the market at a reasonable cost.

With these and other objects in view, the invention consists in the novel construction, arrangement and formation of parts, as will be hereinafter more specifically described, claimed, and illustrated in the accompanying drawings, in which:

Figure 1 is a vertical central section through our improved gas heater;

Figure 2 is a horizontal section taken on the line 2—2 of Figure 1 looking in the direction of the arrows showing our improved burner in top plan;

Figure 3 is a detail end view of the fresh air pipe illustrating the valve for controlling the entrance of the fresh air into the mixing chamber;

Figure 4 is a detail horizontal section taken on the line 4—4 of Figure 1 looking in the direction of the arrows showing the conical baffle in top plan;

Figure 5 is a horizontal section taken on the line 5—5 of Figure 1 looking in the direction of the arrows showing the conical baffle in bottom plan;

5 Figure 6 is a vertical section through the conical baffle taken on the line 6—6 of Figure 7;

10 Figure 7 is a horizontal section through the conical baffle taken on the line 7—7 of Figure 6 looking in the direction of the arrows;

15 Figure 8 is an enlarged fragmentary horizontal section through the conical baffle taken on the line 8—8 of Figure 6 looking in the direction of the arrows and illustrating the formation of the novel hollow feeding fins;

20 Figure 9 is a horizontal section taken on the line 9—9 of Figure 1 looking in the direction of the arrows showing the burner in top plan;

25 Figure 10 is a horizontal section taken on the line 10—10 of Figure 1 looking in the direction of the arrows illustrating the connection of the air and gas mixing pipe with the gas burner;

30 Figure 11 is an enlarged fragmentary vertical section illustrating in detail the connection between the conical baffle, the burner and the humidifying cup, and

35 Figure 12 is an enlarged fragmentary vertical section illustrating in detail the air supply for the burner and showing the valve plate for controlling the direct supply of air to the burner.

40 Referring to the drawings in detail, wherein similar reference characters designate corresponding parts throughout the several views, the letter A generally indicates our improved heating appliance which includes a casing 15 formed of sheet metal or the like, which receives the burner proper 25, the conical baffle 45 and the fume and heating drum 55.

45 The casing 15 includes side and end walls 16 and 17 and a bottom wall 18. The side and end walls can be provided with an outward turned lateral attaching flange 19 for connection with the floor 20 of a building B, which is to be heated. These side and end walls can also be provided with an inwardly extending flange 21 for supporting a floor register, which can be raised when it is desired or necessary to light the burner.

50 Extending into the lower end of the casing 15 through one end wall 17 thereof is an air pipe or chamber 22 having its inner end closed and its outer end open for connection with a head 23 which receives the air and gas mixing pipe 24 disposed above the air pipe or chamber 22 and which air and gas mixing pipe 24 communicates with the burner proper 25, which will now be described.

55 The burner 25 comprises an annular flared body including the inner and outer spaced walls 26 and 27 and a top wall 28 having a

plurality of burner outlet openings 29 therein. The upper edge of the outer wall 27 extends above the top wall 28 to provide a flange 30 which forms a seat for the conical baffle 45, which will be later described. The lower edges of the inner and outer walls 26 and 27 are provided with annular ribs 31 which are fitted in annular grooves 32 formed in the top face of the plate 33 which is fitted on top of the air pipe or chamber 22 and around an air outlet opening 34 therein. Thus the plate 33 forms a bottom wall for the burner and the burner assembly is secured by means of bolts 35 to the air chamber 22, which bolts extend through suitable radially extending lugs 36 formed on the outer wall 27 of the burner.

60 Thus it is to be noted that the inner wall 26 of the burner flares outwardly from the opening 34 and constitutes a central air passageway for conducting air above the burner openings 29.

65 The air mixing pipe 24 leads into the burner through one side thereof as at 37 so that the air and gas will tend to flow around the burner and thus be evenly distributed to the burner openings 29. The forward end of the mixing pipe 24 is flared as at 38 toward its outer end and is likewise extended into the head 23 and the entrance of air into the mixing pipe 24 is controlled by a slide valve plate 39 which is provided with a guide rod 40 extending through the upper and lower walls of the head 23. The lower end of the rod is provided with a weight 41 for normally maintaining the valve plate 39 in a closed position and a suitable chain 42 is connected to the upper end of the rod and extended to the desired point and operated in any preferred way for opening said valve. A fresh air conduit pipe 43 receives the head 23 and this pipe is extended to the exterior of the building for drawing fresh air into the device. A gas feed pipe 44 is led into the mixing pipe 24 adjacent to the forward end thereof so as to feed gas in the air stream and either natural or artificial gas can be employed. From the construction so far, it can be seen that a free flow of air is permitted into the air chamber 22 and thence into the central portion of the burner and that air under control is admitted into the mixing pipe or chamber 24 and combines with the air and enters into the burner itself.

70 As stated, the flange 30 forms a seat for the conical baffle 45 which forms an important feature of our invention and which will now be described.

75 Our improved conical baffle 45 includes a plurality of equi-distantly spaced radially extending hollow fins 46 which converge toward the lower ends thereof and the lower ends of the fins are connected by an annular plate or wall 47 having openings 47' therein communicating with the hollow fins. The

upper ends of the fins 46 are closed and are connected by an annular vertically disposed ring 48 having its upper end internally threaded as at 49 for the reception of the fume chamber or drum 55. The lower end of the ring 48 is provided with an inwardly extending annular ground seat 50 which also has connection with the drum as will be later described. This ring 48 is provided with a plurality of outlet openings 51 which communicate with the interior of the conical baffle between the threaded portion 49 of the ring and the seat 50, as can be readily seen by referring to Figure 6 of the drawings. The lower face of the annular plate 47 at its periphery is rabbeted as at 52 for receiving the flange 30 and for forming an intimate contact therewith and the inner face of the plate is likewise provided with a ground seat 53 for a purpose which will also be later described. The spaces between the hollow fins 46 form air circulating slots 54, for a purpose which will be later brought out.

Referring to the fume drum or chamber 55, the same includes an annular hollow vertically disposed outer rim portion 56 and a central depending hub portion 57 which is connected with the hollow rim 56 by hollow tubular arms or spokes 58. The central hub portion 57 of the fume chamber includes inner and outer spaced walls 59 and 60 defining an annular chamber 61 therebetween and the lower edge of the outer wall 60 is threaded so as to have threaded connection with the threaded portion 49 of the conical baffle. The inner wall 59 extends below the outer wall 60 and is provided with a flared seat 62 for engagement with the ground seat 50 on the baffle and when the baffle is threaded on the drum, the seat or flange 62 will be forced on its seat to form an intimate contact with the baffle. Communicating with one side of the rim 56 of the fume chamber or drum 55, is the fume outlet pipe 65 which likewise leads to the exterior of the house or building. We prefer to lead the fume outlet pipe 65 through the air inlet pipe 43 to the exterior of the building so that the said pipe will form a protection therefor and thus prevent accident should the fume pipe 65 become overheated and to also permit the incoming fresh air to be preheated by said pipe prior to the entrance of the fresh air into the burner and above the burner.

We can also arrange a pivoted damper 66 in the length of the pipe 65 which damper is normally held in an open position by a weighted arm 67 and the damper can be closed when necessary by a suitable cable or chain 68.

In conjunction with the burner we utilize a humidifying device which embodies a humidifying cup 69 which is fitted within the ground seat 53 of the conical baffle 45 and closes the lower end thereof. If desired, this

cup 69 can be cemented or otherwise secured in place to form an air tight joint. Any preferred means can be utilized for maintaining a constant level of water or other liquid in the cup and as shown, a supply pipe 70 leads into the bottom of the cup and a sediment trap 71 can be employed for cleaning out and catching the dirt. Thus moisture is supplied to the heated air giving a beneficial heat.

We arrange a pilot burner 72 directly above one of the burner openings and a suitable pilot supply pipe 73 can be led from the point of gas supply.

In operation of our improved device, it is to be noted that fresh air is led into the air chamber or pipe 22 thence into the central portion of the burner above the burner openings 29 and into the fins 46 of the conical baffle 45 and that the space between the fins, the moisture cup and the burner constitutes a combustion chamber as well as the hollow fins themselves, and a hollow fin is disposed above each burner opening 29. Air is also admitted into the mixing chamber 24 which mixes with the gas from the pipe 44 and this mixture flows into the burner and out of the burner openings 29 where the same is ignited. The products of combustion flow up through the hollow fins into the hub 57 of the fume chamber, through the hollow arms 58 thereof into the hollow rim 56 and thence out into the fume conduit pipe 65 to the atmosphere. The air to be heated circulates around the fins and around the drum and up through the register into the house to be heated, and thus the air becomes warmed through contact with the fins and also prevents the fins from becoming overheated.

By this arrangement there is no possible chance of any of the fumes or products of combustion from the gas burner entering into the air being heated for the house and the direct flow of air conveying the products of combustion out of the burner at all times, leading to the exterior of the house.

We can provide a plug 75 in the fume chamber 55 for initially lighting the burner and when the burner is lighted the valve plate 39 is allowed to move to its fully closed position, thus cutting off the supply of air to the burner proper and a match is then applied to the plug opening, which will ignite the gas and the pilot burner 72. The plug 75 is now threaded back into place and the valve 39 can be raised to supply the proper amount of air to the burner.

By raising and lowering this valve plate 39, the proper burning of the device can be regulated.

The damper plate 66 is utilized for facilitating the lighting of the burner and is especially useful in cold weather and this damper can be moved to its closed position upon the initial lighting of the burner and to momentarily retain the gas in the baffle 130

so that all of the burner openings will become ignited.

We can also employ a depending baffle plate or pipe to partially surround the conical baffle 45, so as to protect the walls of the casing from undue heat and to lead the air to be heated under and around the conical baffle 45 and thence around the fume chamber 55 to the room to be heated.

10 If desired, the gas heater can be placed in a cabinet in a room, instead of the casing 15, as shown.

Changes in details may be made without departing from the spirit or the scope of this 15 invention.

What we claim as new is:

1. A heating appliance comprising an air chamber having an air outlet opening, a gas burner of hollow annular construction having a plurality of burner outlets and fitted 20 over the air opening, an air and gas mixing pipe communicating with the hollow burner, a head receiving the air chamber and the air and gas mixing pipe, a fresh air conduit pipe 25 connected to the head and leading from the outside of the building to be heated, means for controlling the flow of air into the air and gas mixing pipe, an air heating baffle arranged to receive the air from the air chamber and the products of combustion from the 30 burner, and means for receiving the products of combustion from the baffle and for leading the same exteriorly of the building.

2. A heating appliance comprising an air chamber having an air outlet opening, a hollow annular gas burner surrounding the opening, an air and gas mixing pipe communicating with the hollow burner, the burner being provided with a plurality of burner outlet 35 openings, a gas supply pipe communicating with the mixing pipe, a fresh air pipe having communication with the air chamber and the air and gas mixing pipe and leading from the exterior of the building to be heated, means 40 for controlling the entrance of air into the air and gas mixing pipe, an air heating baffle arranged over the burner for receiving the products of combustion therefrom, a fume chamber arranged on the air heating baffle 45 for receiving the products of combustion, a fume conduit pipe leading from the fume chamber to the exterior of a building to be heated, and a normally open damper in said fume pipe.

55 3. A heating appliance comprising an air chamber having an air outlet opening, a hollow annular gas burner surrounding said opening and having a plurality of burner outlets, an air and gas mixing pipe communicating with the burner and arranged substantially tangential thereto, a gas supply pipe 60 communicating with the air and gas mixing pipe, a fresh air conduit pipe leading from the exterior of a building to be heated and 65 having communication with the air chamber

and the air and gas mixing pipe, a valve for controlling the flow of air into the air and gas mixing pipe, a conical air heating baffle including a plurality of hollow radially extending fins arranged over the burner for receiving the products of combustion therefrom, a fin being disposed above each burner opening, a humidifying cup received in the conical air heating baffle and sealing the lower end thereof for leading the products of combustion into the hollow fins, a fume chamber fitted over the conical baffle and having an annular inner wall engaging the inner portion of the baffle and having the interior thereof communicating with the hollow fins for receiving the products of combustion therefrom, and a fume conduit pipe communicating with the fume chamber and leading to the outside of the building to be heated.

4. A heating appliance comprising an air chamber having an air opening therein, an annular hollow gas burner ring surrounding said opening and provided with a plurality of gas burner outlets, an air and gas mixing pipe communicating with the hollow burner ring, 85 a gas supply pipe leading into said air and gas mixing pipe, a fresh air conduit pipe communicating with the air chamber and air and gas mixing pipe, means for controlling the flow of air into said air and gas mixing pipe, a pilot burner for the gas burner, the gas burner being provided with an annular flange seat at its upper edge, a conical baffle member including a plurality of downwardly converging hollow fins and a bottom 90 plate provided with openings communicating with the fins, a hollow fin being arranged above each burner opening, the ring being rabbeted at its periphery to fit upon said flange seat, the inner face of the plate being provided with a ground seat, an annular vertically disposed ring connecting the upper 95 ends of the fins and having openings therein communicating with the upper ends of said hollow fins, a fume chamber including an annular hollow rim, a hollow central hub portion and radially extending hollow spokes connecting the rim and the hollow hub together, the hub including an inner depending wall connected with the lower portion of the ring of the baffle and an outer wall connected with the upper end of the ring of the baffle, a humidifying cup fitted on the seat of the plate, means for supplying liquid at a constant level to the cup, and a fume conduit 100 pipe communicating with the hollow ring of the fume chamber and extended to the exterior of a building.

5. A heating appliance comprising an air chamber having an air opening therein, an annular hollow gas burner ring surrounding said opening and provided with a plurality of gas burner outlets, an air and gas mixing pipe communicating with the hollow burner ring, a gas supply pipe leading into said air 105

- and gas mixing pipe, a fresh air conduit pipe communicating with the air chamber and air and gas mixing pipe, means for controlling the flow of air into said air and gas mixing pipe, a pilot burner for the gas burner, the gas burner being provided with an annular flange seat at its upper edge, a conical baffle member including a plurality of downwardly converging hollow fins and a bottom plate provided with openings communicating with the fins, a hollow fin being arranged above each burner opening, the ring being rabbeted at its periphery to fit upon said flange seat, the inner face of the plate being provided with a ground seat, an annular vertically disposed ring connecting the upper ends of the fins and having openings therein communicating with the upper ends of said hollow fins, a fume chamber including an annular hollow rim, a hollow central hub portion and radially extending hollow spokes connecting the rim and the hollow hub together, the hub including an inner depending wall connected with the lower portion of the ring of the baffle and an outer wall connected with the upper end of the ring of the baffle, a humidifying cup fitted on the seat of the plate, means for supplying liquid at a constant level to the cup, a fume conduit pipe communicating with the hollow ring of the fume chamber and extended to the exterior of a building, said fume conduit pipe being extended through the fresh air inlet pipe and provided with a control damper, and a housing for the burner, the baffle and the fume chamber.
7. A heating appliance comprising an air chamber having an air opening therein, an annular hollow gas burner ring surrounding said opening and provided with a plurality of gas burner outlets, an air and gas mixing pipe communicating with the hollow burner ring, a gas supply pipe leading into said air and gas mixing pipe, a fresh air conduit pipe communicating with the air chamber and air and gas mixing pipe, means for controlling the flow of air into said air and gas mixing pipe, a pilot burner for the gas burner, the gas burner being provided with an annular flange seat at its upper edge, a conical baffle member including a plurality of downwardly converging hollow fins and a bottom plate provided with openings communicating with the fins, a hollow fin being arranged above each burner opening, the ring being rabbeted at its periphery to fit upon said flange seat, the inner face of the plate being provided with a ground seat, an annular vertically disposed ring connecting the upper ends of the fins and having openings therein communicating with the upper ends of said hollow fins, a fume chamber including an annular hollow rim, a hollow central hub portion and radially extending hollow spokes connecting the rim and the hollow hub together, the hub including an inner depending wall connected with the lower portion of the ring of the baffle and an outer wall connected with the upper end of the ring of the baffle, a humidifying cup fitted on the seat of the plate, means for supplying liquid at a constant level to the cup, a fume conduit pipe communicating with the hollow ring of the fume chamber and extended to the exterior of a building, said fume conduit pipe being extended through the fresh air inlet pipe and provided with a control damper, and a housing for the burner, the baffle and the fume chamber.
6. A heating appliance comprising an air chamber having an air opening therein, an annular hollow gas burner ring surrounding said opening and provided with a plurality of gas burner outlets, an air and gas mixing pipe communicating with the hollow burner ring, a gas supply pipe leading into said air and gas mixing pipe, a fresh air conduit pipe communicating with the air chamber and air and gas mixing pipe, means for controlling the flow of air into said air and gas mixing pipe, a pilot burner for the gas burner, the gas burner being provided with an annular flange seat at its upper edge, a conical baffle member including a plurality of downwardly converging hollow fins and a bottom plate provided with openings communicating with the fins, a hollow fin being arranged above each burner opening, the ring being rabbeted at its periphery to fit upon said flange seat, the inner face of the plate being provided with a ground seat, an annular vertically disposed ring connecting the upper ends of the fins and having openings therein communicating with the upper ends of said hollow fins, a fume chamber including an annular hollow rim, a hollow central hub portion and radially extending hollow spokes connecting the rim and the hollow hub together, the hub including an inner depending wall connected with the lower portion of the ring of the baffle and an outer wall connected with the upper end of the ring of the baffle, a humidifying cup fitted on the seat of the plate, means for supplying liquid at a constant level to the cup, a fume conduit pipe communicating with the hollow ring of the fume chamber and extended to the exterior of a building, said fume conduit pipe being extended through the fresh air inlet pipe and provided with a control damper, a housing for the burner, the baffle and the fume chamber, and a depending baffle plate arranged in the casing around the fume chamber and baffle and terminating short of the lower end of said casing.
- In testimony whereof we affix our signatures.
- ALBERT B. MILLER.
- WALTER H. KELLNER.
